(57) **CLAIM**

The ornamental design for a popsicle mold as shown and described.

DESCRIPTION

FIG. 1 is a perspective, exploded view of the ornamental design for a popsicle mold, showing our new design;

FIG. 2 is a front elevation exploded view;

FIG. 3 is a side elevation exploded view;

FIG. 4 is a perspective view;

FIG. 5 is a side elevation view;

FIG. 6 is a cross-section view taken along the line 6-6 of FIG. 5;

FIG. 7 is an exploded view with popsicles inverted for use;

FIG. 8 is a top plan exploded view; and,

FIG. 9 is a bottom plan exploded view.

The broken lines in the drawings depict portions of the popsicle mold that form no part of the claimed design. The popsicle portions shown in broken lines in FIG. 7 are for the purpose of showing environmental structure and forms no part of the claimed design.
